(57) **CLAIM**

The ornamental design for an auxiliary cyclonic dust collector, as shown and described.

DESCRIPTION

FIG. 1 is a perspective view of an auxiliary cyclonic dust collector showing my new design;

FIG. 2 is a top view thereof.

FIG. 3 is a right side elevational view thereof.

FIG. 4 is a left side elevational view thereof.

FIG. 5 is a rear view thereof; and,

FIG. 6 is a front view thereof.

The wheels, casters and intake portion shown in broken lines form no part of the claimed design.
